(57) **CLAIM**

The ornamental design for a display rack, as shown and described.

DESCRIPTION

FIG. 1 is a perspective view of the display rack of the present invention;

FIG. 2 is a front elevation view of the display rack of the present invention;

FIG. 3 is a left elevation view of the display rack of the present invention;

FIG. 4 is a right elevation view of the display rack of the present invention;

FIG. 5 is a rear elevation view of the display rack of the present invention;

FIG. 6 is a top plan view of the display rack of the present invention; and,

FIG. 7 is a bottom plan view of the display rack of the present invention.

The broken line showing of supporting structure in FIG. 1 is for illustrative purposes only and forms no part of the claimed design.

The broken line showing of a channel strip attached to the front of the display rack in FIGS. 1-7 is for illustrative purposes only and forms no part of the claimed design.
